UNITED STATES PATENT OFFICE.

WILLIAM PEACE, OF HAMILTON, CANADA.

WINDOW WEATHER-STRIP.

SPECIFICATION forming part of Letters Patent No. 792,286, dated June 13, 1905.

Application filed May 13, 1903. Renewed May 11, 1905. Serial No. 259,959.

To all whom it may concern:

Be it known that I, WILLIAM PEACE, a citizen of Canada, residing at Hamilton, in the county of Wentworth and Province of Ontario, 5 Canada, have invented new and useful Improvements in Window Weather-Strips, of which the following is a specification.

My invention relates to improvements in window weather-strips, and particularly to the 10 horizontal meeting-rail of the sash in which metallic strips, preferably zinc, are inserted and secured in the lower horizontal meeting-rail of the upper sash and in the upper horizontal meeting-rail of the lower sash and horizontally curved or bent in such a manner that 15 the bent part of the strip of the lower sash shall fit into the bent part of the strip of the upper sash.

The object of my invention is to provide the 20 horizontal meeting-rail of the upper and the lower sash with means for protecting the room of a house from the weather or storms. I attain this object by the mechanism illustrated in the accompanying drawings, in which—

25 Figure 1 is a front elevation of a window sash and frame. Fig. 2 is a sectional side elevation of the same, showing the metallic weather-strips inserted in position in the horizontal meeting-rail of the upper and the lower sash. Fig. 3 is an enlarged detail view of the 30 horizontal meeting-rails of the sash with the strips in position, as in Fig. 2 of the drawing. Fig. 4 is an enlarged detail section of the detached metallic strips in relative position.

35 In the drawings the upper sash is represented by A and the lower sash by B. The oblique lines 2 and 2, as seen in Fig. 3 of the drawings, are the meeting or joining rail parts of the sash. The meeting-rail A is provided with a rabbet 3 in its side and top adjacent the meeting-rail B. Secured to the 40 top of the meeting-rail A is a metallic strip 4, having a U-shaped portion received in the rabbet 3.

45 The metallic strip 6 is attached to the upper

part of the meeting-rail B of the lower sash, and the overhanging bent edge 7 of the strip 6 extends downward to conform to and to fit loosely in U-shaped edge 5 of the strip 4. The strips 4 and 6 extend lengthwise with the 50 meeting-rails A and B of the sash. It will be noticed that the bent part 7 of the strip 6 is also U-shaped to give strength and stability to the same. This shape is important to prevent the possible creasing of the part 7 of the 55 strip and to retain the said bent part in horizontal line in order that the bent part 7 may always freely leave and enter the U-shaped part 5 of the strip 4 of the upper sash when the said sash is raised or lowered, as the case 60 may be. It will be obvious that with the device as set forth that the upper sash may be lowered or that the lower sash may be raised, either one or both, as desired.

The construction and attachment of the horizontal metallic strips to the horizontal meeting-rails of the sash prevents the storms and extreme cold weather from penetrating through the joint 2 of said rails in a most satisfactory manner.

What I claim as my invention, and desire to 70 secure by Letters Patent, is—

In a weather-strip, the combination with the meeting-rails, of a metallic strip secured flush with the top of the lower rail of the 75 upper sash and having a U-shaped portion depending at right angles to the secured portion and seated in a rabbet in said rail, and a right-angle strip one side of which is secured flush with the top of the upper rail of 80 the lower sash, the other side of said strip depending at right angles to the secured portion and being bent back upon itself to said secured portion, said last-named portion adapted to enter the rabbet and be engaged by the 85 U-shaped strip.

WILLIAM PEACE.
